CLAIM

We claim the ornamental design for an interchangeable battery, as shown and described.

DESCRIPTION

FIG. 1 is a perspective view of an interchangeable battery showing our new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines and the areas within are for the purpose of illustrating portions of the interchangeable battery that form no part of the claimed design.
